UNITED STATES PATENT OFFICE

CARL P. DOUGLASS, OF CHICAGO, ILLINOIS, ASSIGNOR TO CHICAGO PENNANT COMPANY, OF CHICAGO, ILLINOIS, A CORPORATION OF ILLINOIS

SHIPPING CASE

Application filed March 9, 1928. Serial No. 260,334.

My invention relates to shipping cases, and particularly to shipping cases adapted to serve as parcel post laundry cases or containers.

5 One of the objects of the invention is to provide a simple, practical, and advantageous form of shipping case.

Another object of the invention is to provide an advantageous construction of shipping case involving an inner stiff box or container made of material similar to cardboard, pasteboard, or the like, and an outer case or cover preferably made of a flexible fabric such as canvas or like material.

10 Another object of the invention is to provide a construction of inner box or case which may be inexpensively made in quantity, and which will be stiff and rigid enough to strongly resist outside pressure.

15 Another object of the invention is to provide a construction of outer case or covering, which may be advantageously and inexpensively made, and which will readily accommodate a stiff inner box or case.

20 Another object of the invention is to provide an advantageous material for making the stiff inner box or case.

Another object of the invention is to arrange for the making of the outer case or cover from a single piece of fabric or like material.

25 Another object of the invention is to arrange for effective tightening of the outer case or cover on the inner case or box.

30 Another object of the invention is to arrange an effective means for holding a shipping tag in place and for readily inserting and withdrawing such a tag.

35 In the accompanying drawings:

40 Fig. 1 is a perspective view of a shipping case embodying my invention;

Fig. 2 is a cross section of the same;

Fig. 3 is a longitudinal section taken on line 3—3 in Fig. 2;

45 Fig. 4 is a perspective view of the interior box or case.

Fig. 5 is a view of a piece of fabric or similar material out of which the outer case or cover may be made.

50 Figs. 6 to 12 inclusive, are views of said

blank in process of being formed into an outer fabric case or cover.

Fig. 13 is a perspective view of the finished outer case or cover by itself, and Fig. 14 is a cross section taken on line 14—14 in Fig. 1.

55 Referring to the drawings I show in Figs. 1, 2, and 3, the complete shipping case comprising an outer case or cover 1 preferably made of some fabric material such as canvas or the like, and the inner box or case 2 preferably made of some stiff material such as cardboard, pasteboard, or the like, and fitted snugly within the outer case or cover 1. In Fig. 4 I show this inner case or box 2 by itself—that is, without the outer case or cover 1.

60 The outer case or cover 1 is preferably made of a single piece of material bent and sewed to make the case by a method or process which will be later referred to. In its completed form, however, this outer case or cover 1 appears as shown in Figs. 1, 2, and 3, in which it completely encloses the inner box 2 covering it on all sides and on top and bottom, the outer cover 1 being also preferably provided 65 with encircling straps 3—3, and a top strap 4 which serves to hold certain portions of the case 1 effectively tightened, and also serves as a handle for carrying the device. The construction of this outer case or cover 1, 70 will be best understood by referring to Figs. 5 to 12 inclusive, showing the manner in which the same is made, and to Fig. 13, showing the completed device.

75 In Figs. 5 to 12 a single piece of material 80 is in the form of a rectangular blank 5 is shown, and from this blank the case or cover 1 is made by folding and stitching in a certain manner. In Fig. 5 this blank 5 is shown

spread out and in a flat condition. In this blank are fastened or secured certain strips or straps of material such as webbing leather or the like, and these strips or straps become the straps 3 previously referred to as shown

85 in Fig. 1 for example. In the way in which the cover 1 is made up from the blank 5, these strips or straps 3 are secured or fastened as by sewing, to the underside of blank 5, and therefore appeared in dotted lines in Fig. 5.

90 At one end for example, the lower end of each

strap 3, there is a buckle 6, and the other end of each strap for example, the upper end is adapted to fit and work in the corresponding buckle 6, said upper ends preferably provided with metal end pieces or clips 7.

6 The blank 5 is provided with certain lines or markings where it is to be folded, and where it is to be sewed as will be described. At its lower end, the blank is provided at its 10 corners with diagonal lines 10, and vertical lines 11, and cross or horizontal lines 12. At its middle portion, it is provided with oppositely inclined horizontal lines 13 and vertical or longitudinal lines 14, and cross or 15 horizontal lines 15 and 16. At its upper end the blank is provided with diagonal lines 17 similar to lines 13 and cross lines 18, and vertical or longitudinal lines 19.

First the blank is folded along lines 11—11 20 by moving the outer corner portions 20 and the outer edge portions 27 upwardly, and then downwardly so as to fold such portions 20—27 down substantially over the body portion of the blank, making creases 21—21 as shown 25 in Fig. 6. Lines 10—10 will then appear in reverse position as shown in said Fig. 6.

Next the corner portions 23 are folded about the lines 10—10, so that these corner portions 23 will lie flat upon the bottom portion of the blank as is shown in Fig. 7. The corner portions 20 are doubled under the portions 23 as shown in said Fig. 7. Stitching or 30 sewing is then extended along the edges 23^a, so as to secure said edges to side portions 27.

35 Next the bottom portion 22 is swung upwardly so that it assumes a substantially vertical position, that is, an upright position considering that the blank 5 is still in a flat position. This portion 22 swings up about 40 a line 12^a extending between the lines 12—12. As this movement takes place, the stitched edges or corners 23^a swing outwardly and upwardly and the side portions 27 also swing outwardly and upwardly so that the bottom 45 portion 22 and the side portions 27—27 form upwardly extending rim portions at right angles to one another, and the seams 23^a—23^a form rectangular corners between said portions 22, 27—27, as shown in Fig. 8. The 50 portions 23 which were folded down now assume an upright position and the corner portions 20 are doubled back upon themselves in loop form, as shown in said Fig. 8. Tape 26 is stitched along the edge of upright portion 22, and around the corners 23^a so as 55 to bind the edge of said portion 22, and also hold the corners 23^a and parts forming the same together. This tape 26 will hold the looped portions of the corners 20 against 60 the edge portion 22.

Next the material is folded along diagonal lines 13—13, the result of which is to move or swing the upper portion of edges 27 upwardly so that said edges 27 will stand in a 65 substantially vertical or upright position

from their lower ends to the lines 13, as shown in Fig. 9. At this time lines 16 will extend vertically upward, and will be superposed upon or in contact with lines 14, which latter will extend up vertically as will also 70 the material of the blank between lines 14, said material being drawn or pulled upwardly by the folding of the blank about lines 13. Stitching or sewing will then be extended along the aligned lines 16—14, and thus a 75 structure will be made or formed with a bottom 5^a, a lower upright wall 22, side upright walls 27—27, and a top upright wall 28, all as shown in said Fig. 9.

Next the blank is folded along the lines 18—18 and intermediate line 18^a so that the top edge portion 30, will lie practically over or above the adjacent portion of the blank, as shown in Fig. 10. Then the corner portions 31—31 are bent or folded along lines 17—17, as shown in Fig. 11, so that said corner portions 31 come into position over or above the folded down edge or marginal portion 30, and stitching is then applied along the edges 18—18 formed along lines 80 18—18.

Next the marginal or edge part 30 is swung upwardly so as to form a substantially upstanding or vertical edge or wall portion 30, as shown in Fig. 12, the side portions 33 also 85 extending up vertically adjacent to the wall 30, so that a structure with upright end wall 30 and side wall and side upright walls 33—33 is formed. Tape 34 is preferably applied 90 along the edges of wall 30 and also along the side of walls 33.

Thus, the blank 5 shown in Fig. 5, a single piece of rectangular material such as canvas or other fabric may be formed into an outer case or cover, such as shown in Fig. 105 12. In this arrangement the lower part of the device illustrated by the rectangular structure, having walls 22 and 27, is to receive the inner rigid case or box such as the structure shown in Fig. 4. The upper portion of the arrangement shown in Fig. 12, is to be folded down and used to cover the top of the inner case 2 which, otherwise is to be exposed and to be drawn and held firmly and tightly about the same.

In Fig. 12 this outer case or cover is shown ready to receive the inner box or case, and to have its upper portion folded down over the same. In Fig. 13 this outer case or cover is shown, still empty or without the inner box, but with its upper portion swung or folded down so as to almost close the lower portion.

This Fig. 12 shows the outer case or cover which we have described so in detail in the process of making. The various parts and features described in connection with Figs. 5 to 12 inclusive will appear and at once be recognized in this Fig. 13. The receiving portion or holder 35, having the upstanding walls 22, 27—27 is shown below the upper 125 130

covering portion 36, which latter is swung about the line 15^a in order that the upper or cover portion 36 may be moved and pulled down over the lower receiving portion 35.

5 The straps or strips 3—3 are then in a depending position, as shown in Fig. 13, and the strap 4 is in a position ready to be connected with the buckle 4^a of another strap 4^b. These two straps 4 and 4^b are secured as by stitching to corner or angular formations 38, which are at the back end of the structure, as shown in Fig. 13, which portion of the structure, however, becomes the top when the device is in position for holding or carrying or resting as shown in Fig. 1. These portions 10 38 are formed by the projecting ears shown in Fig. 9 which develop at the middle of the cover blank, when the same is bent by lines 13—13 as described in connection with Fig. 9, and is also shown in Fig. 12. When the upper 15 or cover portion 36 of the cover is swung down a bit, the projecting portions may be bent toward one another so as to form the ears or flaps 38, and these may be folded down and against the adjacent part of the case as previously referred to.

The inner box or case 2, shown particularly in Fig. 4 may be of any preferred or desired construction to go with the outer case or cover 1. However, I show a highly advantageous form of construction in Fig. 4, which involves a box made with a body portion 2^a and a pair of hinged cover flaps 2^b, which have their meeting edges preferably cut so as to dove tail or mortise as shown in Fig. 4, one part 20 being provided with a recess 2^c and the other with a tongue 2^d, which fits in, but overlaps the recess 2^c, the end portions 2^e, overlapping the adjacent portions of the other cover section, so that an interlocking arrangement is 25 secured. This makes a firm and rigid wall for the inner box or case, which strongly resists external pressure. If desired, the other side of the case or box 2 may be made in a similar manner as illustrated in dotted lines in Fig. 4.

30 45 While the box or case 2 may be made of any suitable material, I preferably make it of a material which I find to be particularly advantageous by reason of its strength, rigidity and workability. This material consists of 50 a central chip filler 46, and outer cylinder kraft liners 47. This practically doubles the Mullen test strength of the box, and also practically eliminates the breaking point, that is the material may be bent back and forth on its scoring marks without breaking the liners.

To assemble the complete device, inner box or case 2 is placed in the receiving portion 35 of the outer case or cover 1, and then the upper portion 36 of said case 1, is swung or folded down so that it will cover and enclose the box receiving or inner portion 35. The device thus arranged is shown in Figs. 1, 2, and 3.

55 The encircling straps or strips 3—3, have their ends fastened together as by passing the

metal end pieces 7, 7 through the buckles 6, 6, and then pulling strongly and firmly upon the ends of said straps 3, so as to tighten them around the device.

These straps or strips 3 are preferably 70 sewed to the top member 38, down to nearly the lower edge of the wall 30, as shown in Fig. 13, so that when said straps are tightened, the tightening pressure or pull is exerted practically at the edge of wall 30, and thus substantially the entire width of said wall is pulled or tightened, thereby preventing any wrinkling or looseness on the part of said wall.

Middle parts of the portions of the strips or straps 3—3 which extend across the top member 38, are also preferably left unsewed, as shown in Fig. 13, thereby leaving short, unfastened or unsecured parts of said strips which form slots or sockets for receiving the end portions 40 of a frame or holder 41, for a 80 shipping tag 42. The ends 40 of this frame or holder 41 are preferably reduced in width so as to be narrower than the body portion of frame 41, thereby forming shoulders 43 on frame 41, so that when tongues 40 are pushed underneath loose portions 3^a of straps 3, said frame or holder 41 will be held in position by the straps 3, and this holding or retention will be firm and secure when the straps 3 are tightened by their buckled ends. When said 85 straps 3 are not tight, however, the holder 41 may be removed by withdrawing its tongue ends 40, and the card or shipping tag 42 may be changed or replaced as desired. In this way, a very simple, inexpensive, and effective construction is provided for holding the shipping tag and its holder, and for manipulating the same so as to make any change or substitution desired.

The strips or straps 3 also have other short portions or parts which are not sewed or secured namely, parts 3^b on the end or edge of the case which becomes the top when the case is in position in Fig. 1. These unsecured portions 3^b are to permit the passage of the 90 strap 4 and the ready movement of said strap so as to allow it to be tightened, and thereby tighten the corner pieces 38. The strap 4 may also serve as a handle for lifting and carrying the device.

95 By tightening the strap 4 and members 38, a further effective pulling strain is applied to the cover 1, due to the fact that these members 38 are triangular or pointed in shape, and their outer ends are substantially the 100 width of the small ends of the device, whereby the tightening of strap 4 will apply strong pressure to both the upstanding ends of the device, and also to the bottom of the said ends.

105 Thus, a very advantageous case is provided with a cover which may be made of a single piece of material which can be readily applied to the inner boxlike structure, and may be readily tightened and firmly secured for 110 115 120 125 130

shipping; and with a simple and inexpensive form of shipping tag holder, and at the same time a stiff inner box or case may be provided in a very simple, practical, and inexpensive manner.

It will be understood that changes may be made without departing from the spirit of the invention.

What I claim is:

10. 1. In a device of the class specified, the combination with a casing of a pair of straps arranged side by side and secured to said casing, said straps having corresponding unsecured portions formed with shoulders to engage and hold the ends of a shipping card holder in place.
20. 2. In a device of the class described, a rectangular casing body and a rectangular cover having one side in common made of a single rectangular piece of material with the separating corners each formed by folding in a square of surplus material at each corner as two right angle triangles which are sewed to an adjacent side and having loose triangular projections at the end of said common side formed by folding the surplus material at the ends of the common side when the body and cover are shaped, and the said projections of said cover having straps connected to each of the loose projections, one of said straps having a buckle thereon whereby said projections are drawn into position and held.
30. 3. In a device of the class described, a rectangular casing body and a rectangular cover having one side in common made of a singular rectangular piece of material with the separating corners each formed by folding in a square of surplus material at each corner as two right angle triangles which are sewed to an adjacent side and having loose triangular projections at the end of said common side also connected to the upright sides, and straps secured to said projections for tightening all three of the sides of the casing body and the cover when said strap is drawn taut.

In witness whereof, I hereunto subscribe my name this 28th day of February, A. D., 1928.

CARL P. DOUGLASS.
